UNITED STATES PATENT OFFICE.

DANIEL BROR WESTIN, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

PLATEN-SHIFTING MECHANISM FOR TYPE-WRITERS.

1,013,084.

Specification of Letters Patent.

Patented Dec. 26, 1911.

Application filed August 13, 1907. Serial No. 388,326.

To all whom it may concern:

Be it known that I, DANIEL BROR WESTIN, residing at Hartford, in the county of Hartford and State of Connecticut, have invented 5 certain new and useful Improvements in Platen-Shifting Mechanism for Type-Writers, of which the following is a full, clear, and exact description, such as will enable others skilled in the art to which it 10 appertains to make and use the same.

This invention relates to typewriting machines and is directed more especially to improvements in mechanism employed for shifting the platen for different case printing.

One of the objects of the invention is to provide means for shifting the platen to a position at either side of a normal central position so as to enable the same to receive 20 impressions from any one of three types mounted upon each type-bar.

Another object thereof is to provide simple and efficient means for shifting the platen such that while the same is always 25 held firmly in a normal central or intermediate position it may be readily shifted to a printing position to either side thereof.

A further object of my invention is to provide mechanism of the above character 30 which will operate to shift the platen in a silent manner and which will accurately determine the position of the platen in its normal position as well as in its shifted positions.

35 Other objects will be in part obvious and in part pointed out hereinafter.

The invention accordingly consists in the features of construction, combinations of elements and arrangement of parts which 40 will be exemplified in the construction hereinafter set forth, and the scope of the application of which will be indicated in the following claims.

In the accompanying drawings wherein 45 is illustrated one of the various possible embodiments of my invention; Figure 1 is a view in vertical section taken through a typewriting machine equipped therewith, the shifted positions of the platen and the 50 mechanism employed to shift the same being shown in dotted lines. Fig. 2 is a hori-

zontal sectional view taken substantially on line *a*—*a*, Fig. 1 showing certain of the operative parts of my invention in plan. Fig. 3 is a view in elevation of a portion of the 55 mechanism illustrated in Fig. 2. Fig. 4 is a diagrammatic view of a fixed cam employed herein showing the form of the cam track.

Similar reference characters refer to similar parts throughout the several views of the drawings.

In the accompanying drawings wherein my invention is shown applied to a machine of the front strike type 1 indicates a portion of the framing of the machine provided with a bed 2, upon which is supported a bank of type-bars, one of which is shown at 3, said type-bars being adapted to be projected against the common printing point 70 upon the platen by means not shown herein. The platen 4 in the present instance is carried by a frame 5 which slides in a way 7 provided in an upwardly extending member or horn 8 of a tie-rod 9 which extends 75 fore and aft of the machine and is anchored in the front portion thereof as at 10.

Extending transversely of the machine and journaled in the lower ends of a bracket 11 depending from tie-rod 9 is a shaft 12, 80 said shaft having at either end thereof an arm 13, which carries a rail 14, upon which the platen frame is supported. The platen frame rides upon rail 14 during its letter spacing movements and said rail is adapted 85 to be lifted or depressed to shift the platen. Rail 14 is carried upon standards 15, which ride in ways 16, formed in the machine frame. Arms 13, which extend through slots provided in standards 15, are adapted 90 to be swung upwardly and downwardly by oscillatory movements of shaft 12, and thereby through rail 14, shift the platen from a normal intermediate position in which the same is adapted to rest to a position 95 at either side thereof by mechanism which will presently be described. At this point it may be noted that the above mechanism forms no part of my present invention, but is described in order to render the same 100 clearer of understanding. Certain parts thereof are included in an application of

Charles W. Sponsel filed of even date herewith.

Shaft 12 has fixed thereon at one end an arm 17, which extends downwardly 5 therefrom, the lower end of said arm being pivotally connected at 18 to a lever 19, and this lever at its opposite end has a roll 20 journaled thereon. Roll 20 is adapted to travel in a cam track 21 provided in a member 22 secured, in the present instance, 10 to the left-hand wall of the machine. The cam track 21 is formed upon arcs of different radii so that when roll 20 is caused to traverse the same lever 19 will be projected end-wise in opposite directions, thereby through arm 17 rocking shaft 12 in opposite directions, whereby the platen through arms 13 will be caused to be raised or lowered from its normal intermediate 15 position. The cam track has a dwell 23 at its intermediate portion and similar dwells 24 and 25, at the upper and lower ends respectively, the form of these dwells being such that a slight movement of roll 20 20 thereover will not operate to project lever arms 19 in an endwise direction to shift the platen. The dwells moreover, through the above described mechanism, operate to determine the position of the platen in its 25 shifted or in its intermediate position, that is, when roll 20 occupies dwell 23 the platen will be located in its intermediate position, and when said roll occupies either of dwells 24 or 25 the platen will be located 30 in its raised or lowered printing position respectively.

A link 26 is pivotally connected to lever 19 intermediate its ends at 27, and the lower end of this link has a similar connection at 40 28 with the free end of a floating lever 29. The point of connection of floating lever 29 with link 26 is adapted to be swung upward or downward to move lever 19 in corresponding directions, as will presently be 45 made apparent.

Extending fore and aft of the machine at the left hand side thereof, and journaled upon a stud shaft 30, extending laterally from the rear portion of the framing of the 50 machine, are a pair of shift levers 31 and 32 respectively. Lever 31, which is the longer of the two, is adapted to lift the platen, the shorter of said levers being adapted to depress the same. Floating lever 29 is disposed intermediate these levers and has its forward end connected to shift lever 31 by means of a pivot screw 33. Floating lever 29 is provided intermediate its ends with a slot 34 within which is located a slot block 55 35 supported upon a stud 36 fixed to shift lever 32. It will therefore be seen that floating lever 29, being attached to each of the shift levers at a different point in its length, will cause link 26 to move upwardly when 60 65 shift lever 31 is depressed, said floating lever

swinging upon slot block 35 as a point of pivotal support and will be caused to move link 26 in an opposite direction when shift lever 32 is depressed, and in this case said lever will swing upon pivot screw 33 as a stationary pivot. The swinging movements of the floating lever when the shift levers are depressed are indicated by the dotted lines in Fig. 1.

Means are provided for holding one of the 75 shift levers stationary while the other is depressed, whereby the stationary lever may operate as a means of pivotal support for the floating lever during the depression of the other shift lever, said means in the present instance, comprising a ball 37 carried by a rod 38, which hangs from a bracket 39 upon the framing of the machine, said ball being disposed intermediate the shift levers, as clearly shown in Fig. 2 of the drawings. 80 Ball 37 is of such width as to be engaged by either shift lever when depressed and projected underneath the other shift lever, thereby holding the same against downward movement.

Shift levers 31 and 32 are both held in upward positions by means of springs 40 and 41 attached thereto and to a suitable post extending from the frame of the machine. In their upward position the shift levers bear 95 against a pad 42 and in their downward position are arrested by means of a pad 43 secured to a suitable bracket as at 44 provided upon the frame of the machine.

To the forward end of each of shift levers 100 31 and 32 are attached locking members 45 and 46 respectively, said locking members having hooks 47 and 48 adapted when the shift levers are depressed to take under locking plates 49 and 50 secured by means of a 105 bracket 51 to the side wall of the framing of the machine. Locking members 45 and 46 which have finger keys 52 and 52' at their upper portions are normally held in a position shown in Fig. 1 by means of leaf 110 springs 53 and 54, in which position their hooks will clear the locking plates during the depression of the key levers. However, if during the depression of a shift lever one of these locking members is engaged by the 115 finger of the operator the hook thereof may be readily swung beneath one of the locking plates, thereby locking the key lever in its lowered position. When it is desired to unlock the key lever a slight exertion of pressure thereon will enable its spring to return the locking member to its normal position. Having thus described the construction of this embodiment of my invention, the operation thereof may now be understood. It will be understood from the above 120 description that the depression, for instance of shift lever 31 will cause floating lever 29 to lift link 26 and thereby swing lever in an upward direction, causing roll 20 to traverse 125 130

the upper portion of cam track 21. At this point it may be noted that the upper portion of cam track 21 is formed upon a smaller radius than the central portion, so that when 5 roller 20 is moved to the upward position lever 19 will be moved rearwardly, causing arms 13 to elevate the platen. The lower portion of cam track 21 is formed upon an arc of larger radius than the upper portion 10 so that when roller 20 has been moved to the lower position lever 19 will be moved toward the front of the machine, which movement will depress arms 13 and move the platen to its lower printing position. This 15 latter movement will be effected by a depression of shift lever 32 which will operate to depress lever 29 through shift lever 32 and link 26. Springs 40 and 41 connected with shift levers 31 and 32 respectively operate 20 to return the same to their normal positions and also to return lever 19 to the position shown in the drawings, in which position roll 20 thereof occupies dwell 23 of the cam track, the carriage being in intermediate position. During each of the above described 25 movements of shift levers 31 and 32 the shift lever not depressed is held rigidly against downward movement by means of the ball lock attached to the swinging rod 38. It 30 will accordingly be seen that I have provided mechanism of the above type, well adapted to attain, among others, all the objects and aims of my invention in an exceedingly simple yet efficient manner. The 35 platen is held immovable in a normal intermediate position, thus allowing erasures to be made without causing the platen to be depressed under the pressure necessarily employed to effect such operations. The platen 40 is, moreover, automatically locked in either its raised or lowered position, and the engagement of the cam roll with the dwells of the cam track operate to determine the shifted position of the platen, as well as the intermediate position thereof. The shifting 45 operation is also noiseless, owing to the fact that concussion or impact of moving parts is entirely eliminated.

As many changes could be made in the 50 above construction and many apparently widely different embodiments of this invention could be made without departing from the scope thereof, it is intended that all matter contained in the above description or 55 shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention, what I

claim as new and desire to secure by Letters Patent is:

1. In a typewriting machine, the combination with the shiftable platen, of a pair of shift levers, a cam, and a lever having a connection with said shift levers and with said cam adapted to shift the platen in opposite directions from an intermediate printing position. 70

2. In a typewriting machine, in combination, a platen shiftable in opposite directions from a normal intermediate position, a cam, a lever connected with said cam and with the platen, and a pair of shift levers, each of which has a connection with said first lever and adapted to move the same in opposite directions whereby the platen may be shifted in opposite directions from its normal printing position. 75

3. In a typewriting machine, in combination, a platen shiftable in opposite directions from a normal intermediate position, a cam, a lever connected with said cam and with said platen, a pair of shift levers, each of which has a pivotal connection with said first lever and adapted to swing the same in opposite directions whereby the platen is shifted in opposite directions from its normal printing position, and means for restoring the platen to normal position. 85

4. In a typewriting machine, in combination, a shiftable platen normally held in an intermediate position and adapted to be shifted in opposite directions therefrom, a cam, a lever having a connection with said platen and with said cam, and a second lever having a pivotal connection with said first lever and adapted to transmit motion to swing the same in opposite directions thereby shifting the platen from its intermediate 100 position to a position at either side thereof. 105

5. In a typewriting machine, the combination with a shiftable platen normally held in an intermediate printing position, of means for moving said platen to either side of said 110 normal position for different case printing, comprising a pair of shift levers, a lever pivotally connected to each of said shift levers, a cam, and a second lever operatively connected with said cam and having a connection with said first lever and also with the platen. 115

6. In a typewriting machine, in combination, a shiftable platen normally held in an intermediate printing position, a pair of 120 shift levers for raising or depressing the platen to other printing positions, a lever common to both of said shift levers and pivotally connected to each, a cam, a second lever operatively connected with said cam 125 and with said first lever, and means for connecting said second lever with the platen.

7. In a typewriting machine, in combination, a shiftable platen, a pair of shift levers, a lever pivotally connected at a different 130

points with said shift levers, a second lever, a cam with which one end of said second lever is operatively connected, and means for connecting the opposite end of said latter lever with the platen, said first lever being adapted to swing upon either of its points of attachment with the shift levers as a fulcrum to shift the platen to either side of its normal position.

10 8. In a typewriting machine, in combination, a shiftable platen normally resting in an intermediate printing position, a pair of shift levers, a lever to which both of said shift levers are pivotally connected at different points in the length thereof, a cam, and lever mechanism connecting said first lever with the platen and with said cam, the pivotal connection of said first lever with one of said shift levers operating as a stationary fulcrum when the other of said shift levers is depressed.

15 9. In a typewriting machine, in combination, a shiftable platen, a pair of shift levers, a lever pivotally connected at a different point in its length with each of said shift levers, a member having a cam track formed upon arcs of different radii, a second lever connected with said first lever and having one of its ends operatively connected with 20 said cam, and a connection between the opposite end of said lever and the platen, said first lever being adapted to swing upon either of its points of connection with a shift lever as a fulcrum when the other of 25 said shift levers is depressed, thereby swinging said second lever with respect to said cam track and shifting the platen to a different printing position.

10 10. In a typewriting machine, the combination with a shiftable platen, of a pair of shift levers, a lever connected at different points in its length with each of said shift levers, a member having a cam track formed upon arcs of different radii, a lever having a 40 member adapted to traverse said cam track, said lever being connected with the platen and also with said first lever, said first lever being adapted to swing upon its pivotal connection with one of said shift levers as a fulcrum to swing said second lever in one direction from its initial position when the other shift lever is depressed and to swing upon its pivotal connection with the other shift lever as a fulcrum when the first shift lever 45 is depressed whereby the platen will be shifted in another direction.

11 11. In a typewriting machine, the combination with a shiftable platen, of a lever connected therewith and adapted to shift the same in opposite directions from an intermediate printing position, a member having a cam track formed upon arcs of different radii, said lever being adapted to traverse said cam track, a second lever connected 60 with said first lever, and a pair of shift le-

vers each of which is pivotally connected to said second lever at a different point in its length, the pivots connecting said second lever with said shift levers acting as stationary fulcrums or as points of application of power to swing said lever in different directions whereby the platen will be shifted in a direction dependent upon the particular shift lever depressed.

12. In a typewriting machine, the combination with a shiftable platen adapted normally to rest in an intermediate printing position, a member having a cam track formed upon arcs of different radii, a lever connected with said platen and having one end connected with said platen and the opposite end thereof operatively connected with said cam track, a pair of shift levers, and a lever pivotally connected to each of said shift levers at a different point in its length, the pivotal connection of one of said shift levers operating as a stationary fulcrum about which said last mentioned lever swings when the other shift lever is depressed.

13. In a typewriting machine, the combination with a shiftable platen, of a pair of shift levers, lever and cam mechanism connected with each of said shift levers and with the platen adapted when one of the shift levers is depressed to shift the platen in an upward direction and when the other thereof is depressed to shift the platen in a downward direction, and means adapted automatically to hold one of said shift levers in a raised position during a depression of the other.

14. In a typewriting machine, the combination with a shiftable platen normally resting in an intermediate position and adapted to be shifted to either side thereof for upper or lower case printing, of a pair of shift levers, a pivotally mounted rod depending from a fixed portion of the frame of the machine and extending between said levers, and a ball or similar device carried by said rod and adapted to be engaged by one of said members when depressed and projected beneath the other thereof, whereby the latter lever will be locked in its raised position while the other is being depressed.

15. In a typewriting machine, in combination, a platen adapted to be shifted to either side of a normal printing position for upper or lower case printing, a pair of shift levers, a lever pivotally connected to each of said shift levers and having a connection with the platen, and means actuated by each of said shift levers for holding the other thereof stationary during a depression of one thereof, whereby the pivotal connection of each of said shift levers with the second mentioned lever operates as a stationary fulcrum about which the latter swings to shift the platen.

16. In a typewriting machine, in combi-

nation, a shiftable platen, a pair of shift levers extending fore and aft of the machine and pivoted upon a fixed pivot located in the rear portion thereof, a lever connected to each of said shift levers intermediate their ends, a cam, and a second lever connected with said first lever and operatively connected with said cam and also with the platen.

17. In a typewriting machine, in combination, a shiftable platen, a pair of shift levers, a lever connected to each of said shift levers and adapted to be swung upon its pivotal connection with one of said shift levers when the other thereof is depressed, a member having a cam track, a second lever carrying a roll adapted to traverse said cam track, said lever being connected with the platen, and means for connecting said last mentioned levers.
- 20 18. In a typewriting machine, the combination with a shiftable platen, of a pair of shift levers, a lever having a pivotal connection with each of said shift levers, a member having a cam track formed upon arcs of different radii, a link pivotally connected with said lever, a second lever pivotally connected with said link, a roll journaled on said second lever adapted to traverse said cam track, and a connection between said second lever and the platen.

19. In a typewriting machine, the combination with a shiftable platen normally held in an intermediate printing position, of means for moving the platen to either side of said normal position for different case printing, comprising a pair of shift levers, a lever pivotally connected to each of said shift levers, a cam track, a lever carrying a member adapted to traverse said cam track and having a connection with the platen, and a link connecting said levers.

20. In a typewriting machine, the combination with a shiftable platen normally held in an intermediate printing position, of a pair of shift levers, a lever pivotally connected at different points in its length with said shift levers, a member having a cam track constructed upon arcs of different radii, a lever having a member adapted to traverse said cam track and having a connection with the platen, and a link connecting said first and second mentioned levers, said second lever when swung in one direction being adapted to shift the platen in one direction from its intermediate position, and when swung in the opposite direction to shift from such intermediate position, said cam track being so constructed as to determine the intermediate or shifted positions of the platen.

21. In a typewriting machine, the combination with a shiftable platen normally held in an intermediate printing position, of a pair of shift levers, a lever to which both of said shift levers are pivotally con-

nected at different points in the length thereof, a member having a cam track formed upon arcs of different radii, a lever carrying a roll adapted to traverse said cam track, a connection between said latter lever and the platen, and a link connecting said levers, the last mentioned of said levers being adapted when swung in different directions to shift the platen in different directions from its intermediate position in accordance with the particular shift lever depressed, said cam track being provided with dwells adapted to determine the position of the platen in either its intermediate or shifted positions.

22. In a typewriting machine, in combination, a shiftable platen, a pair of shift levers extending transversely of the machine and pivoted upon a fixed pivot located in the rear portion thereof, a lever connected to each of said shift levers intermediate their ends, a member having a cam track formed upon arcs of different radii, said cam track having dwells at its opposite ends and at its intermediate portion, a roller adapted to traverse said cam track, a lever carrying said roll and having a connection with the platen, and a link connecting said levers and said last mentioned lever when swung in either direction by the first mentioned lever, being adapted to shift the platen to either side of its intermediate position, such shifting being effected by the traversing of said roll upon said cam track.

23. In a typewriting machine, the combination with a shiftable platen, of means for shifting the platen to either side of an intermediate printing position for different case printing, comprising a pair of shift levers, a floating lever pivotally connected to each of said shift levers, a fixed cam, a lever carrying a member adapted to traverse said cam and having its opposite end connected with said platen, a connection between said latter lever and said floating lever adapted when the floating lever is swung in either direction to cause the member carried by said second lever to traverse said cam track, whereby the platen will be shifted in either direction from its intermediate position in accordance with the particular shift lever depressed.

24. In a typewriting machine, the combination with a shiftable platen, of means for shifting the same from an intermediate position to a printing position to either side thereof, comprising a pair of shift levers extending transversely of the machine and fulcrumed in the rear portion thereof, a floating lever having a pivotal connection with each of said shift levers, whereby when one of said levers is depressed the pivotal portion of the other shift lever with said lever operates as a fulcrum upon which the latter swings to shift the platen, a link

carried by said floating lever, a second lever connected to said link, a member having a cam track formed upon arcs of different radii, a roll or similar device carried by said second lever adapted to traverse said cam track, and a connection between the opposite end of said second lever and the platen.

In testimony whereof I affix my signature, in the presence of two witnesses.

DANIEL BROR WESTIN.
